J. LOFTUS,
HEATING SYSTEM,
APPLICATION FILED APR. 30, 1917.

1,285,262.

Patented Nov. 19, 1918.

John Loftus
Inventor
By Fred C. Billman, Atty.

UNITED STATES PATENT OFFICE.

JOHN LOFTUS, OF ALBANY, NEW YORK.

HEATING SYSTEM.

1,285,262.

Specification of Letters Patent. Patented Nov. 19, 1918.

Application filed April 30, 1917 Serial No. 165,345.

To all whom it may concern:

Be it known that I, JOHN LOFTUS, a citizen of the United States, residing at Albany, in the county of Albany and State of New York, have invented certain new and useful Improvements in Heating Systems, of which the following is a specification.

My invention relates to improvements in heating systems, the primary object of the invention being to provide a generally improved combined hotwater and steam heating system, the various parts and features therein being so arranged and disposed as to effect a positive and rapid circulation of the heat carrying and distributing vehicle through the heating circuit in an automatically controlled manner as hereinafter fully described.

Generally speaking my improved heating system comprises a suitable boiler or generator provided with a circuit of suitable feed and return pipes and radiators, together with a valved by-pass interposed between and communicating with the said pipes and connections to said generator for causing the flow of the fluid through said pipes as well as automatically causing a change in the level of the heated liquid and permitting steam and water to pass alternately through the circuit upon changes in the water level and in the pressure in the generator and pipe system as will herein-after more fully appear.

With the above mentioned and other ends in view, the invention consists in the novel construction, arrangement, and combination of parts hereinafter described, illustrated in one of its embodiments in the accompanying drawings, and particularly pointed out in the appended claims.

Referring to the accompanying drawings, forming a part of this specification, Figure 1, is a side elevation of one form or embodiment of my improved heating system, as applied to or installed in a building having three floors.

Fig. 2, is a detailed view, partly in side elevation and partly in section, of the improved boiler or generator with the outlet and inlet connections co-operating with the feed and return pipes of the improved system.

Fig. 3, a longitudinal sectional view taken on line 3—3 of Fig. 1.

Similar numerals of reference designate

like parts throughout all the figures of the drawings.

The improved heating system comprises a suitable generator or water heater 1, 60 which may be of any suitable form or type, and is provided with a circuit of pipes comprising, in the present instance, a feed pipe 2, and a return pipe 3. The return pipe 3, preferably includes, at suitable intervals and at different levels, a plurality of cross or horizontally extending pipes 2^a, the latter being provided with suitable radiators 2^b, and such horizontal pipes 2^a and radiators 2^b, may be provided with valves 70 2^c, but as this system is intended to operate as an open coil system, the valves 2^c, are normally open, and for this reason may be dispensed with. An adjustable valve 3^a, permits the escape of air therethrough when 75 fluid is being forced through the pipes by the generator—as for example—in starting the improved system, the adjusting wheel 3^b, permitting of an adjustment of the tension of a spring 3^c, on the valve 80 3^a in an obvious and well known manner in accordance with any desired pressure in the pipe system and forming a safety valve therefor.

To control the flow of hot water and 85 steam through the pipes and radiators, a by-pass 4 is interposed between, and is adapted to provide communication with, the feed and return pipes 2 and 3, said by-pass 4 being provided with a controlling 90 valve 4^b. When the controlling valve 4^b is open, the by-pass 4, and connecting feed and return pipes 2 and 3, together with the lowermost pipe 2^a, and the lowermost radiator 2^b, form a hot water circuit while 95 the feed and return pipes 2 and 3, and the radiators above the by-pass 4, will form a steam heating circuit, the system being filled with water to a point above the by-pass 4, as will later be more particularly described. 100

To cause water and steam to pass alternately through the feed and return pipes from the upper portion of the heater or boiler, as in the normal operation of the system, later described the boiler is provided with a connection 5, having therein the separate conduits 5^c and 5^d, whose outlet and inlet portions 5^a and 5^b, respectively, terminate at different levels, said outlet 5^a terminating at a higher level within the 110 boiler than said inlet 5^b, the outlet 5^a communicating through conduit 5^c with the

supply pipe 2, and the inlet 5^b communicating through conduit 5^a with the return pipe 3.

To permit the fluid in the feed and return pipes to flow in but one direction, the feed pipe 2 is provided with a check valve 2^a, and the return pipe 3 is provided with a check valve 3^a. The pressures in said feed and return pipes may be indicated by the pressure 10 gages 6 and 7.

Before the system is put into operation, the heater is filled with water to a point above the lower end of the outlet 5^a, and, in operation, it will be understood that the 15 water is normally above the level of said outlet portion 5^a, near the top of the boiler, and a certain steam space is provided above the water. When a certain steam pressure is reached, hot water will be forced out 20 through the outlet 5^a, and into the feed pipe 2, and, if desired, all or a portion of such hot water may be passed through the by-pass 4, and thence through the lower radiator and its connecting pipe 2^a, and down through the 25 return pipe 3, returning to the boiler or generator through the inlet 5^b, and when the pressure of the steam and hot water in the circuit is sufficient to cause the level of the water to go below and thus to unseal or open 30 the outlet 5^a, steam will pass through said outlet portion and into the circuit until such time as the water level in the boiler again rises and seals said outlet 5^a, whereupon, hot water will again be forced into the feed pipe. 35 Where a substantially balanced condition prevails, steam and hot water will alternately be passed into the fluid outlet portion 5^a, and through the circuit of the system, as well known in the "geyser system" to which 40 this invention relates.

When it is desired to transform the feed and return pipes 2 and 3, above and below the by-pass 4, into steam and hot water circuits, respectively, water is filled into the 45 boiler and feed and return pipes to a point slightly above the by-pass 4, and the by-pass is fully opened by fully opening the valve 4^b, thus permitting hot water to circulate through the feed and return pipes 2 and 3, and lower radiator 2^a, the water feeding from 50 and returning to the boiler and through the by-pass as a hot water circuit, and steam being permitted to pass through the circuit above the by-pass 4, as a steam circuit.

If desired, the feed pipe 2, may be provided with a controlling valve 2^a. The generator 1 may be provided with a suitable inlet or feed water pipe 1^a, connected to a suit-

able source of supply and provided with a control valve 1^b.

From the foregoing description, taken in connection with the accompanying drawings, the operation and advantages of my invention will be readily understood.

Having thus described one of the embodiments of my invention, what I claim and desire to secure by Letters Patent, is,—

1. A heating system, comprising a generator, feed and return pipes and radiators connected in series therewith at different levels, a connection having separate conduits terminating within said generator and communicating with said pipes, the conduit communicating with the feed pipe having its inlet terminating at a higher level within said generator than the outlet of the conduit communicating with said return pipe, and a valved by-pass communicating with said feed and return pipes at a level between that of the highest and lowest radiators.

2. A heating system, comprising a generator, a circuit of feed and return pipes communicating therewith, radiators and connecting pipes communicating with said return pipe at different levels, a by-pass interposed between the feed and return pipes at a point above the level of the lowermost radiator forming upper and lower circuits whereby vapor will flow through said upper circuit and heating liquid through said lower circuit and by-pass when the heating liquid is maintained to or above the level of the latter in said system, and check valves in said feed and return pipes between said by-pass and generator to prevent retrograde movement of the heating liquid in said pipes.

3. A heating system, comprising a generator, a circuit of feed and return pipes having their inlet and outlet portions vertically spaced in said generator, radiators and connecting pipes communicating with said return pipe at different levels, the uppermost of said connecting pipes provided with an escape valve, a valved by-pass interposed between and communicating with said feed and return pipes at a level between that of the highest and lowest radiators whereby vapor may be caused to flow through the radiators above said by-pass and liquid through the radiators below said by-pass.

In testimony whereof I have affixed my signature in the presence of two witnesses.

JOHN LOFTUS.
